UNITED STATES PATENT OFFICE.

EDWARD HEISER AND PETER BINKLE, OF BERLIN, ONTARIO, CANADA, ASSIGNEES TO THE GOODYEAR'S METALLIC RUBBER SHOE COMPANY, A CORPORATION OF CONNECTICUT.

COMBINATION RUBBER AND LEATHER FOOTWEAR.

1,271,707.

Specification of Letters Patent.

Patented July 9, 1918.

Application filed June 30, 1916. Serial No. 106,875.

To all whom it may concern:

Be it known that we, EDWARD HEISER and PETER BINKLE, both subjects of the King of Great Britain, residing at Berlin, Province 5 of Ontario, Dominion of Canada, have invented certain new and useful Improvements in Combination Rubber and Leather Footwear, of which the following is a full, clear, and exact description.

10 This invention relates to footwear, comprising soles and uppers of rubber and tops of leather, canvas, or other material secured thereto. It is more particularly directed to an article of the kind described having the 15 lower edge of the leather or other top lying against and secured to the face of the shoe upper.

Footwear of the kind mentioned, while possessing certain desirable characteristics, 20 has heretofore caused chafing and actual cutting of the foot, more particularly at the heel, through contact of the latter with the sharp edge of the leather top adjacent its junction with the rubber upper. It is accordingly 25 the aim of this invention to provide an article which, while presenting the substantial qualities and attractive appearance of the type of shoe mentioned, shall include a simple device for preventing injury to 30 the heel or other part of the foot at which the chafing mentioned may occur.

For a detailed description of a preferred form of our invention, reference may be had to the following specification and accompanying drawing forming a part thereof, in which:

Figure 1 represents a perspective view of a shoe embodying our invention including a top provided with an extension made up of 40 one or more pieces secured to the quarters of the top and to one another;

Fig. 2 represents a partial section on the line 2—2 of Fig. 1;

Fig. 3 represents a detail view showing a 45 modified extension made up of pieces integral with the two quarters of the top.

Referring to the drawing the numeral 1 indicates a rubber upper provided with a sole 2 and a top 3, preferably of leather, 50 consisting of two quarters 4 and 5 having their lower edges underlying and forming a lap-joint with the upper edge of the rubber upper 1, the edges of the quarters terminating adjacent the upper edge of the rubber upper except adjacent the heel. The

joint is secured by sewing the parts together with stitches projecting through the rubber upper and lying in longitudinal channels 6 forming the troughs of a corrugated rim at the edge of the upper. The rim protects 60 the stitches from wear. The quarters are sewed together at the rear and form a seam in the usual manner at 7 covered exteriorly by the back-strap 8.

Extending from the lower back portions of 65 the quarters as shown in Figs. 1 and 2 are substantially identical members 9 and 10 sewed along the line 11 providing a butt joint and forming a substantially central seam aligned with the seam 7. The extension is 70 sewed to the quarters along the line 12 and also provides a butt joint therewith. The extension as well as the pieces 9 and 10 comprising it are of generally oblong outline with the lowermost corners rounded. The extension 75 may be modified as shown in Fig. 3 by forming the members 13 and 14 corresponding to members 9 and 10 integrally with the quarters 4 and 5.

The extension projects downwardly so 80 that its lower edge lies substantially adjacent to the inner surface of the insole 15. By virtue of the butt joint formed between the extension and the lower edge of the top, the extension forms a flush surface with the top, 85 and at the same time lies freely against the inner back surface 16 of the rubber upper. This smooth flush surface disposed symmetrically with respect to the back seam and located at that portion of the shoe where 90 chafing is most apt to occur prevents such chafing and permits the shoes to be worn without any discomfort from that cause.

Having thus described our invention what we claim as new and desire to protect by Letters Patent is:

1. An article of footwear comprising an upper, a top underlying and secured to the uppermost edge of said upper, a sole, said top having a portion terminating adjacent 100 said edge, and an extension projecting therefrom to a position adjacent said sole providing a smooth continuous surface lying against the inner surface of said upper.

2. An article of footwear comprising an 105 upper, a top having its lower edge underlying and forming a lap-joint with the uppermost edge of said upper, a sole, a portion of the edge of said top terminating adjacent the edge of said upper, and an extension pro- 110

- jecting from the lower rear portion of said top to a position adjacent said sole providing a smooth continuous surface lying freely against the rear inner surface of said upper.
5. An article of footwear comprising a rubber upper, a leather top formed of two quarters joined together by a seam at the back and having their lower edges underlying and forming a lap-joint with the uppermost edge of said upper, an extension formed by complementary pieces of leather extending respectively from the lower back portion of said quarters and joined together along a seam aligned with the seam of said quarters, and a sole, said extension projecting to a position adjacent said sole and providing a surface flush with the inner surface of said quarters and lying freely against the inner back surface of said upper.
10. An article of footwear comprising an upper, a top underlying and secured to the uppermost edge of said upper, the lower edge of the top terminating adjacent the upper edge of the shoe upper except at the heel, and a sole, a portion of the top being extended at the heel to a position adjacent the sole and providing a smooth continuous surface adapted to prevent chafing of the wearer's heel.
15. A boot or shoe comprising an upper member and a top member, said members being secured together along their upper and lower margins respectively to form a lapped joint, the inner lap forming an exposed offset edge at approximately the height of the said upper member for a portion of the distance about the boot or shoe terminating at the heel portion, the inner lap at said heel portion being extended for a substantial distance beyond said edge.
20. An article of footwear comprising an upper, a top underlying and secured to the uppermost edge of said upper, the
